UNITED STATES PATENT OFFICE.

CHARLES C. WORTHINGTON, OF IRVINGTON, NEW YORK.

PUMP.

SPECIFICATION forming part of Letters Patent No. 597,368, dated January 11, 1898.

Application filed November 21, 1896. Serial No. 612,944. (No model.)

To all whom it may concern:

Be it known that I, CHARLES C. WORTHINGTON, a citizen of the United States, residing at Irvington, county of Westchester, and 5 State of New York, have invented certain new and useful Improvements in Pumps, fully described and represented in the following specification and the accompanying drawings, forming a part of the same.

10 In many processes of manufacture—such as sugar-making, tanning, distilling, brewing, &c.—it is impracticable to use the common composition suction and force valve seats set into cast-iron on account of the corrosive action of the liquid, which attacks the joints between the seats and iron and rapidly destroys them, so as to cause a leak from one side of the valve-plate to the other. It is important, therefore, that the valve- 15 plates, including the valve-seats, be made entirely of a material or composition not injuriously acted upon, and this result is secured economically by interposing separate valve-plates of suitable material between the 20 iron castings forming the water-cylinder and the suction and force chambers.

25 The object of the present invention is to provide a construction of this class employing such separate valve-plates which shall be simple, cheap, and efficient and especially to 30 provide a construction which shall avoid irregular forms and consequent expense, secure short and direct passages between the suction and force chambers, so as to avoid extended 35 or tortuous passages and internal joints subjected to the action of the fluid, and reduce as far as practicable the floor-space occupied by the machine. This result is secured by 40 arranging the valve-plates edgewise in relation to the water-cylinder, instead of flatwise, as usual; and the present invention includes, broadly, a pump having a valve-plate arranged edgewise to the water cylinder or cylinders with the suction and force chambers 45 at the side of the plate. Many arrangements of the cylinders and pulsation, suction, and force chambers may be made embodying this invention; but in the preferred construction for a double-acting pump the suction and force 50 chambers are arranged between the valve-plates for the opposite ends of the cylinder,

and such a construction forms a part of the present invention.

The invention includes also various specific features of construction, some of which 55 relate to duplex pumps, and the invention therefore will be illustrated in connection with such a pump.

For a full understanding of the invention a detailed description of a construction embodying all the features of the same in their preferred form will now be given in connection with the accompanying drawings, forming a part of this specification, in which—

Figure 1 is a longitudinal vertical section 65 of the water end on one side of a duplex pump which may be of any suitable general construction, such as that of the well-known duplex pump built by Henry R. Worthington. Fig. 2 is a vertical cross-section on the line 70 2 of Fig. 1. Fig. 3 is a vertical cross-section on the line 3 of Fig. 1. Fig. 4 is a horizontal section on the line 4 of Figs. 1 and 2.

Referring to said drawings, A A' are the water-cylinders on opposite sides of the pump, 75 and B B' the pulsation-chambers for the opposite ends of the cylinders; C and D, the suction and force chambers, which are common to the two sides of the pump; E, the suction-main, and F the force-main. As shown, the 80 pulsation-chambers are arranged vertically above the opposite ends of the pump-cylinders and connected therewith by short passages, and these pulsation-chambers are separated from the suction and force chambers 85 by the composition valve-plates G, which are arranged edgewise to the cylinders and extend transversely thereto and are shown as provided with the common voluntary suction-valves *a* and force-valves *b*, between which 90 valve-plates are the suction and force chambers.

In the preferred construction shown the pulsation-chambers for the opposite sides of the pump are cast integral, a single casting 95 having the integral vertical partition 10, forming the two chambers for the opposite sides at each end of the cylinders, and the suction and force chambers common to both sides of the pump are formed by a single casting having the integral horizontal partition 11, dividing the force from the suction chamber. 100

A single valve-plate G at each end of the cylinders is used, these plates having valve-seats, preferably integral therewith, for both the suction and force valves, and these valve-plates are secured in place at their edges between the separate castings which form the pulsation-chambers and the suction and force chambers. It will thus be seen that this arrangement of valve-plates edgewise to the cylinders secures the results above stated and is very simple and compact, while at the same time it provides for direct and simple connections for both the suction and force mains and for convenient hand-holes, as shown, by which access is had to all the water-valves. When the chambers and valve-plates for opposite sides of the pump are formed integral and arranged as shown, it will be seen that a construction very simple and cheap of manufacture is provided, but few castings being required and these of simple form.

It will be understood that modifications may be made in the construction shown without departing from the invention, and I am not to be limited to the exact form or arrangement illustrated. Thus while I have shown the valve-plates as extending in planes transverse to the pump-cylinder it will be understood that they may be arranged so as to extend in planes longitudinal of the cylinder in some cases, but that shown is the preferred construction.

While the invention is of especial value in pumps in which the character of the liquid pumped makes it desirable that the valve-seats and valve-plates should be of special material, it will be understood that the use of the invention is not thus limited, but that it may be applied also to other classes of pumps.

While the invention has been illustrated as applied to a double-acting and duplex pump, and certain features of the invention relate to pumps of these classes, it will be understood that it is applicable generally in pump constructions, whether single or duplex. The form of such constructions will be clear from the illustration and description of the duplex pump shown herein.

50. What I claim is—

1. A pump having a valve-plate formed separately from the other parts of the pump and placed edgewise to the pump-cylinder and carrying seats for one or more force and suction valves arranged with one of said valves or sets of valves between the cylinder and the other of said valves or sets of valves, substantially as described.

2. A pump having a valve-plate formed separately from the other parts of the pump and placed edgewise to the pump-cylinder and extending in a plane transverse to the pump-cylinder and carrying seats for one or more force and suction valves with one of said valves or sets of valves arranged between the cylinder and the other of said valves or sets of valves, substantially as described.

3. A pump having suction and force chambers arranged in line with one of said chambers between the other chamber and the cylinder, and a valve-plate formed separately from the other parts of the pump and placed edgewise to the cylinder with the pulsation-chamber on one side and the suction and force chambers on the opposite side of the valve-plate, substantially as described.

4. A pump having suction and force chambers arranged in line transversely to the cylinder, with one of said chambers between the other chamber and the cylinder and a valve-plate formed separately from the other parts of the pump and placed edgewise to the cylinder and extending in a plane transverse to the cylinder, with the pulsation-chamber on one side and the suction and force chambers on the opposite side of the valve-plate, substantially as described.

5. A pump having valve-plates for the opposite ends of the pump-cylinder formed separately from the other parts of the pump and placed edgewise to the pump-cylinder and having the suction and force chambers between the valve-plates, and arranged in line with one of said chambers between the other chamber and the cylinder, substantially as described.

6. A pump having suction and force chambers arranged in line transversely to the cylinder and with one of said chambers between the other chamber and the cylinder, pulsation-chambers on opposite sides of the suction and force chambers, and a single valve-plate for each end of the cylinder formed separately from the chambers and placed edgewise to the cylinder with the suction and force chambers between the valve-plates, substantially as described.

7. A duplex pump having valve-plates for the opposite ends of the pump-cylinders placed edgewise to the cylinders and extending in planes transverse to the cylinder with the suction and force chambers for the opposite sides of the pump between the valve-plates and arranged with one of the chambers for each cylinder between the other chamber and the cylinder, substantially as described.

8. A duplex pump having suction and force chambers for both sides of the pump arranged with one of the chambers for each cylinder between the other chamber and the cylinder, and a single valve-plate at each end of the pump-cylinders for both the suction and force valves and for both sides of the pump placed edgewise to the pump-cylinders with the suction and force chambers between the valve-plates, substantially as described.

9. A duplex pump having at the opposite ends of the cylinders pulsation-chambers integral for both sides of the pump, suction and force chambers for both sides of the pump formed integral with each other, and valve-plates formed separately from the chambers, placed edgewise to the cylinders and extending in planes transverse to the cylinders between

the pulsation-chambers and with the suction and force chambers between the plates, substantially as described.

10. The combination with the cylinders A, 5 A', of the pulsation-chambers B, B' for both cylinders, each formed integral with partition 10, suction and force chambers C, D for the opposite sides of the pump formed integral with the partition 11, and valve-plates G having force and suction valve seats for both sides of the pump and formed separately from and secured between the parts forming the pulsation-chambers and the suction and force chambers, substantially as described.

15 11. The combination with the cylinder A, of the pulsation-chamber B, suction and force chambers C, D formed integral with the partition 11, with one of said chambers between the other chamber and the cylinder, and 20 valve-plate G having force and suction valve seats and formed separately from and secured

between the parts forming the pulsation-chamber and suction and force chambers, substantially as described.

12. The combination with the cylinder A, 25 of the pulsation-chambers B, B' at opposite ends of the cylinder, suction and force chambers C, D between said pulsation-chambers, and arranged with one of said chambers between the other chamber and the cylinder, 30 and valve-plates G having force and suction valve seats and formed separately from and secured between the parts forming the pulsation-chambers and suction and force chambers, substantially as described. 35

In testimony whereof I have hereunto set my hand in the presence of two subscribing witnesses.

CHAS. C. WORTHINGTON.
